UNITED STATES PATENT OFFICE.

ERNST F. ENGSTROM, OF OMAHA, NEBRASKA.

EXTENSION CRUTCH OR CANE.

1,192,290.

Specification of Letters Patent. Patented July 25, 1916.

Application filed August 4, 1915. Serial No. 43,631.

To all whom it may concern:

Be it known that I, ERNST F. ENGSTROM, a citizen of the United States, residing at Omaha, in the county of Douglas and State of Nebraska, have invented new and useful Improvements in Extension Crutches or Canes, of which the following is a specification.

My invention relates to an extension crutch or cane, and the object of the invention is to provide a crutch or cane which may be varied in length as occasion may require, and is thus adapted especially for hospital use, in enabling a single crutch or cane to be employed from time to time by different patients.

A further object of the invention is to provide a crutch or cane having an extensible section which embodies means whereby it may be telescopically adjusted and securely locked in adjusted position.

A still further object of the invention is to provide an extensible crutch having a handle which may be adjusted upon the staff to different positions with relation to the shoulder piece and tread surfaces of the crutch, as the length of the crutch is varied to suit different patients.

The invention consists of the features of construction, combination and arrangement of parts herein fully described and claimed, reference being had to the accompanying drawings in which:

Figure 1 is an outer side elevation of an extension crutch embodying my invention. Fig. 2 is a front elevation of the same. Fig. 3 is an outer side elevation on an enlarged scale of the staff and adjustable handle and showing the construction of the latter. Fig. 4 is a front elevation of the same. Fig. 5 is a detail section on the line 5—5 of Fig. 3. Fig. 6 is a view in elevation of the extension section of the crutch or cane, a portion of the outer tube or sleeve being broken away. Fig. 7 is a vertical longitudinal section through the same. Fig. 8 is a horizontal transverse section on the line 8—8 of Fig. 6 showing the bolt in locking position. Fig. 9 is a view similar to Fig. 8 showing the bolt in released position. Fig. 10 is a vertical longitudinal section on the line 10—10 of Fig. 9.

Referring to the drawings, 1 designates the rod or staff of the crutch or cane, the invention being shown in the present instance as applied to a crutch, although it is

to be understood that it may with equal efficiency be applied to a cane. This rod or staff 1 carries at its upper end a padded shoulder piece 2 and at a suitable point 60 below the shoulder piece an adjustable handle 3. This handle 3 comprises a sleeve 4 provided with yoke arms 5 connected at their extremities by a rod 6 on which is mounted a roller grip 7. The sleeve is provided with a locking spring 8 carrying a dog or pawl 9 in the form of a lug working in an opening in the sleeve and adapted to engage any one of a series of keeper recesses 10 in the rod or staff 1, whereby the handle 70 may be disposed at different elevations on said rod or staff, as occasion may require.

The rod or staff 1 is provided with an extension section 11 comprising a pair of telescopic tubes 12 and 13. The tube 12, is 75 suitably secured at its inner end to the staff 1 and is provided with a threaded and tapered outer end 14 of sufficient resiliency for expansion and contraction and which is engaged by an internally tapered and 80 threaded clamping collar 15, whereby said portion 14 may be expanded and contracted to release or grip the tube 13.

The tube 13 is fitted to slide within the tube 12 to vary the length of the crutch or 85 cane and is closed at its outer end by a threaded tubular holder 16 carrying an elastic shock absorbing tread piece 17 of rubber or other suitable material. The tube 13 is adapted to be secured to the tube 12 in 90 an adjustable manner, and to this end said tube 13 is provided at diametrically opposite sides with slots 18, one wall of each of said slots being provided with notches or recesses 19, while the other wall of each of 95 said slots is bent inwardly to form a combined bracing and stop flange 20. If desired, the flanges 20 may be formed of the metal displaced to produce the slots 18, as will be readily understood.

Carried by the tube 12 is a cross pin or bolt 21 which is slidable in the slots 18 and is adapted to engage and interlock with the notches or recesses 19. As shown, the notches or recesses are arranged in spaced relation 105 at different elevations, and the tube 13 is adjustable through the sliding of the pin 21 in the slots when said slots and pin are in registry, so that the tube 13 may be adjusted to any predetermined extent to bring 110 the locking pin into alignment with opposed recesses at opposite sides of the tube, where-

by said tube may be locked in a variety of adjusted positions.

It will of course be understood that by turning or rotating the tube 13 a part revolution the slots 18 may be brought into and out of alinement with the pin 21 and the slotted portions of the tube 13 thrown into and out of engagement with said pin to lock the tube 13 in any position of adjustment.

10 When the tube 13 is turned to its limit in one direction the pin 21 will be seated in the notches 19 at the same level, while when said tube is turned to its limit in the opposite direction the pin will abut against the flanges 20 which will thus serve as stops, the use of the flanges 20 strengthening the slotted portion of the tube 13 to withstand the imposed strains. When the pin is seated in the desired notches to project the tube 13 to the required extent, the tubes may be clamped against relative motion by screwing up the clamping collar 15, as will be readily understood.

It will thus be seen that my invention provides a rod or staff having a section which may be adjusted to vary the length of the rod or staff, which adjustable or extensible section may be applied to crutches or to canes or to other similar supporting and walking staffs. It will also be seen that through the construction described the length of the staff may be varied while at

the same time the position of the handle may be varied to accord therewith. Of course, in the application of the invention to a cane the handle and shoulder piece will be dispensed with.

The invention will be found of great advantage in the construction and use of crutches and canes for hospitals, etc., in enabling the number of crutches or canes constituting a part of the equipment to be reduced, since the necessity of providing a wide range of different sizes of crutches or canes will be avoided.

I claim:

A device of the character described including a staff, a tube projecting from the staff, a second tube slidably engaging the first-named tube, one of said tubes being provided with longitudinally extending slots and diametrically disposed keeper recesses at opposite sides of said slots, and the other of said tubes having a pin to interlock with said slots, strengthening and bracing flanges upon the slot walls of the slotted tube, and means for holding said tubes against relative movement.

In testimony whereof I affix my signature in presence of two witnesses.

ERNST F. ENGSTROM.
